CONTAINER

Otto Spahr, Philadelphia, Pa.

Application July 28, 1931. Serial No. 553,507

5 Claims. (Cl. 15—134)

This invention relates to an improvement in attachment for containers. More particularly, this invention relates to an attachment for tubes adapted to contain semi-fluid or paste-like substances as, for example, cold cream, lotions, shoe polish, shaving soap or cream, or the like, whereby an applying brush will be provided in combination with the tube.

Heretofore various forms of combined containers and applying brushes have been provided, but have been open to various objections and have proved relatively unsatisfactory.

In accordance with this invention a device is provided for attachment to a tube containing shaving soap, cold cream, shoe polish, and the like, the device being of such a character that the tube will be effectively stoppered and the brush element adequately protected when not in use, and at the same time, the tube may be readily opened for delivery of the contents for application and rubbing by the brush element, which at the same time will be available for application of the tube contents.

Having indicated in a general way the nature and purpose of this invention, I will now proceed to a detailed description of a preferred embodiment thereof in connection with a tube of shaving soap, with reference to the accompanying drawing, in which:

30 Figure 1 is an elevation, partly broken away and partly in section, of a tube of shaving soap in combination with the device involving this invention.

Figure 2 is a plan view of the stoppering and brush protecting element.

35 Figure 3 is a view, partly in section, of the subject of Figure 1, with a stoppering and brush protecting element removed.

In the several figures *a* indicates any ordinary, 40 well known form of tube containing shaving soap, provided, as is usual, with an externally threaded neck *b*. *c* indicates a brush supporting member, circular in form and provided with a central aperture threaded for engagement with

45 the neck *b* of the tube. The member *c* is provided with a peripheral flange *d* and serves to support a brush *e*. The brush *e* is secured to the member *c* within the flange *d*. The brush *e* may be of any structure, but is desirably circular in form 50 with a central aperture and preferably is made of spongy rubber in the form of an annulus, bristle members being formed by slitting on radial lines, as indicated at *f*, *f*, Figure 3.

g indicates a stoppering and brush protecting 55 member, circular in form and provided with a

peripheral flange *h* and a central boss *i*, between which is formed an annular recess or channel *m*.

The boss *i* is provided with a circular recess from its open end, the walls of which are threaded at *j* for engagement with the neck *b* of the 60 tube. At the bottom of the recess is desirably positioned an insert as a cork disk *k*. *n* indicates a soft rubber disk having a central aperture adapting it to be fitted over the neck *b* of the tube *a*, the disc *n* being of such size as to extend over 65

the upper portion of the tube and beyond the shoulder of the tube, as shown in Figure 1. The assembly of the device in accordance with this invention, in combination with a tube of shaving soap, will, it is believed, be obvious from an inspection of Figure 1, from which it will be ob-

served that the washer *n* is slipped over the upper portion of the tube, the member *c* carrying the brush *e* is then threaded on the neck of the tube and finally the stoppering and brush pro-

70 tecting member *g* is threaded on to the neck of the tube through engagement of the threads *j* in the inner wall of the recess formed in the boss *i* with the threads on the neck of the tube.

It will be noted that the under surface of the 75 member *c* is formed to conform with the surface of the tube in its extension from the base of the neck.

When the member *g* is threaded on to the neck of the tube *a*, the brush member *e* carried by the 80 member *c* will extend into the annular recess *m* forced between the boss *i* and flange *h* and the flange *h* will embrace member *c*. When the member *k* is in closing position the tube *a* will be effectively stoppered by engagement of the 85 bottom of the recess in boss *i* or of cork disk *k* with the top of neck *b*.

When it is desired to utilize the embodiment 90 of my invention described, it is only necessary to screw off the member *g*, thus unstoppering the tube *a* and exposing the brush member *e*. The device, as will be obvious, may be used by merely

95 squeezing soap out of the tube *a* and applying it and rubbing up a lather with the brush *e*. It will be noted that the soft rubber washer *n* 100 will prevent injury to the face from the shoulder of the tube, and also prevent the lather from coming in contact with the tube or hands, while the flange *d* on the member *c*, which flange it will be noted is slightly higher than the neck *b* 105 when the member *c* is screwed down upon the neck *b*, will protect the face from injury by the end of the neck *b*, and the sponge rubber brush when in use, will overlap edge of flange *d* to prevent injury to the face thereby.

100

105

110

g indicates a stoppering and brush protecting 55 member, circular in form and provided with a

It will now be noted that by virtue of this invention an efficient combination of a brush with a tube of shaving soap is provided, and in particular a combination of such character as to be efficient in operation with protection against injury to the face by any portion of the tube, and the edge of flange *d*, and of such a character as to insure effective stoppering of the tube and protection of the brush when not in use. It will be noted that the brush is fully protected so that it cannot contact with and soil, for example, clothes with which the tube may be packed in a bag.

It will be appreciated that the brush element may be variously constructed and of various materials depending upon the contents of the tubes. Thus, for example, the brush may be an ordinary bristle brush on annulus of felt, etc. As will be obvious, the device will be operated as described above irrespective of the substance contained by the tubes.

What I claim and desire to protect by Letters Patent is:

1. In combination a tube having a threaded neck, a member adapted for threaded engagement with said neck, a brush carried by said member, a second member adapted for threaded engagement with said neck, said second member being adapted to stopper said tube and being provided with a flange adapted to embrace said first member.

2. In combination a tube having a threaded neck, a member adapted for threaded engagement with said neck, a brush carried by said member, a second member having a central boss and a peripheral flange, said boss being recessed and internally threaded, said boss being threaded upon the neck of the tube and said flange being adapted to surround such first member.

3. In combination a tube having a threaded neck, an annular member provided with a central aperture internally threaded for engagement with said neck, said member being provided with a peripheral flange, an annular brush carried by said member within said flange, a second member provided with a central boss and a peripheral flange, said boss being recessed and internally threaded for engagement with said neck, said flange on said last mentioned member being adapted to embrace said first mentioned member and an insert in said recess in said second mentioned member adapted to stopper said tube.

4. In combination a tube having a threaded neck, an annular member provided with a central aperture internally threaded for engagement with said neck, said member being provided with a peripheral flange, of a height such as to extend beyond the end of the neck when said member is engaged with the neck, an annular brush carried by said member within said flange, a second member provided with a central boss and a peripheral flange, said boss being recessed and internally threaded for engagement with said neck, said flange on said last mentioned member being adapted to embrace said first mentioned member and an insert in said recess in said second mentioned member adapted to stopper said tube.

5. In combination a tube having a threaded neck, a resilient disc extending about the end portion of said tube adjacent to said neck, a member adapted for threaded engagement with said neck, a brush carried by said member, a second member adapted for threaded engagement with said neck, said second member being adapted to stopper said tube and being provided with a flange adapted to embrace said first member.
